ENGINE STARTING APPARATUS

Albert Callsen, Stuttgart-Botnang, Germany, assignor to Robert Bosch Gesellschaft mit beschränkter Haftung, Stuttgart, Germany

Application February 2, 1937, Serial No. 123,624
In Germany February 10, 1936

6 Claims. (Cl. 123—179)

This invention relates to starting apparatus for internal combustion engines, more particularly to a coincidental system in which the operation of the starting motor is instituted by the motion of any suitable control member, such as an accelerator or clutch pedal rather than by an individual starting control. In prior systems of this type there is the possibility that a cold engine may fire a few times and then stop, and that an impatient operator may attempt to re-engage the starting pinion before the engine flywheel has come to rest. Under these conditions considerable damage might be sustained by the starting mechanism. The invention herein described is designed to prevent the occurrence of such damage by providing an interlock linkage arrangement which will prevent the closure of the starting motor circuit until the engine has come to a complete standstill. During the period of engine operation, a coupling element is automatically locked in such position as to render the linkage ineffective and so prevents any improper engagement of the starting switch contacts. When the engine is at a standstill it is necessary to depress the accelerator or clutch pedal in order to unlock the coupling element and restore the linkage to an operative condition. A subsequent depression of the pedal will then actuate the linkage and close the starting switch.

One of the objects of this invention is, therefore, to provide engine starting apparatus which is more efficient in operation and certain in performance.

Another object is to provide engine starting apparatus which is more simple in construction and more economical in manufacture.

A further object is to provide engine starting apparatus which is less subject to injury through abuse or misuse.

Still a further object is to provide engine starting apparatus which is automatically rendered inoperative while the associated engine flywheel is revolving.

Other objects and advantages will in part be obvious and in part be specifically set forth when the following specification is read in connection with the drawings, in which:

Fig. 1 is a side view of the control linkage as applied to a starting motor assembly; Fig. 2 is a fragmentary section taken on line 2—2 of Fig. 1 looking from the left side and showing the coupling bolt in the operative position; Fig. 3 is a partial section similar to Fig. 2 and shows the coupling bolt in its inoperative position; Fig. 4

is a section similar to the two preceding figures and shows the mode of unlatching the coupling bolt to place the linkage in an operative condition; Fig. 5 is a side elevation of the actuating member; Fig. 6 is a cross section taken on line 6—6 of Fig. 7, which shows a modification of the device in which a magnetic starting switch is employed.

Referring now in more detail to Fig. 1, the numeral 1 indicates a starting motor which may be of the type customarily employed in automobile and motor vehicles generally. The armature shaft 2 of the motor carries a sliding pinion 3 which may be moved by the tiltable yoke 4 into engagement with the toothed rim of flywheel 5. The flywheel is attached to an associated internal combustion engine not shown. A starting switch 6 is mounted on the motor 1 in such position that the movable element thereof is in the path of movement of an associated part of the tiltable yoke 4. A bearing 7 on the starter housing supports the yoke 4, the actuating member 8, and the push rod 9, by means of the pivot shaft 10. The push rod 9 is connected to a suitable control, such as the pedal 9' which may be either the clutch or accelerator pedal. As shown in Fig. 2, a latching bolt 11 is transversely mounted in the yoke 4, and is guided by the slots 12 in either leg of the yoke. A spring 13 bears against the top of the bolt 11 and maintains a downward thrust. One end of the bolt projects from the arm of the yoke 4, and is pivotally attached to a lever 14. The bolt 11 has a latch abutment 15 at the other end and is provided with a centrally disposed notch 16. An ear 17 on the yoke 4 pivotally supports the lever 14. The lower end of the lever is connected to a stud 18 which is mounted on a diaphragm 19, mounted in the cup 20. A conduit 21 connects the cup 20 with any suitable source of low pressure, such as the intake manifold of an associated engine. As shown in detail in Fig. 5, the actuating member 8 has a sloping upper surface 22. The forward edge 23 of the member 8 is positioned so that it does not clear the lower edge of bolt 11 when the bolt is in the unlatched position shown in Fig. 2. When the bolt 11 is latched as shown in Fig. 3, the forward edge 23 clears the bottom of the slot 16 and the bolt is engaged by the surface 22 and rear edge 24.

A combined magnetic and lever system is shown in Fig. 7, where the latch bolt 11 is guided in slots 30 in a spring biased, slidible frame 31, best seen in Fig. 6. A coil spring 32 bears against the upper surface of the bolt 11. The actuating

member 33 has the upper surface shaped similarly to the member 8 of the preceding figures and engages the bolt 11 in the same manner. The actuating member 33 is moved by the pivoted lever 34. A push rod 35 is connected to the foot pedal 36, and drives one end of the lever 34 through a spring link 37. An armature 38 of a magnetic switch 39 carries a contact for closing the circuit between a starting motor 40 and the battery 41, the operating winding being indicated at 42 and the customary car ignition switch at 43. An abutment 44 is provided on the slideable frame 31, which engages the end of the switch armature 38. Connected in the ignition circuit through solenoid winding 42 is a generator 45.

The operation of the invention is as follows: In Figs. 2, 3 and 4, the depression of an operating pedal will cause rod 9 (Fig. 1) to move the actuating member 8 from the plane of the paper towards the observer. When the associated engine is stopped there is no vacuum in the intake manifold and the diaphragm 19 is substantially flat, as shown in Fig. 2. This condition draws the latch bolt 11 to the left, where it forms a barrier in the path of the member 8. In starting the engine, the operating pedal forces the member 8 toward the observer, carrying with it the bolt 11, and thus tilting the yoke 4 into engagement with the starting switch, as may be seen from Fig. 1. When the engine starts, the suction in the intake manifold draws the diaphragm 19 into the position shown in Fig. 3, moving the latch bolt 11 to the right and the spring 13 latches it. In case the engine stalls, the linkage remains latched as shown in Fig. 3, and in order to re-start, it is necessary first to depress the operating pedal and move the actuating member 8 forward so that its sloping upper surface 22 will engage the floor of the notch 16 and lift the bolt 11 from its latched position. This may be seen in Fig. 4, where the bolt has been unlatched and the restoring force of the diaphragm 19 is moving it into the position shown in Fig. 2. Whenever there is a suction in the intake manifold of the engine, during either the running condition or in the stopping period, the diaphragm 20 will maintain the bolt 11 in the position shown in Fig. 3. Any movement of the operating pedal will merely cause member 8 to slide through the notch 16, lifting the latch bolt 11 meanwhile, but without tilting the yoke 4. When the engine has come to a complete stop it is necessary, as above mentioned, to first depress the operating member to unlatch the bolt 11 and permit its restoration to the condition shown in Fig. 2. A subsequent depression of the operating member then causes the leading edge 23 of the member 8 to engage the side of the bolt 11, and so tilt the yoke 4 into contact with the starting switch. It will be seen that two separate actuations of an operating member, such as a clutch or accelerator pedal, are necessary to enable operation of the starting mechanism. The first actuation to unlatch the bolt 11 and restore the linkage to an operative condition and the second actuation to tilt the yoke 4 into engagement with the starting switch.

In the embodiment shown in Figs. 6 and 7, the respective action of the bolt 11 and the actuating member 33 is similar to that just described. In this instance, however, when the linkage is in the operative condition and the pedal 26 is depressed the abutment 44 on the slideable frame 31 engages the end of the switch armature 38. The travel of the slideable frame 31 is not sufficient to close the

switch contacts, but it moves the other end of the armature into the strong magnetic field of the solenoid winding 42, assuming that ignition switch 43 is closed. The current flowing from the battery 41, through the winding 42 and armature winding of generator 45 to ground, establishes a magnetic field sufficiently strong to attract the switch armature 38 and close the contacts of the starting motor circuit. When the engine starts the manifold suction will draw in the diaphragm 19 and move the bolt 11 to its inoperative coupling position as shown in Fig. 6. The frame 31 will slide back to the position shown in Fig. 7, and the current coming from the generator 45 will buck the battery current in the solenoid winding to produce a null point which will allow the restoring spring to break the starting circuit and move the armature 38 out of the magnetic field of the solenoid winding. In this embodiment the actual control of the starting switch is virtually independent of the foot pedal assembly 35-36 and the linkage apparatus 31-33. Both of the described embodiments, however, require two operations of the foot pedal in starting, one to place the linkage in operative condition, and the other to close the starting switch.

It will be obvious that many changes and modifications may be made by anyone skilled in the art, without departing from the scope and spirit of the invention as defined in the following claims.

Having described the invention, what is claimed is:

1. In a motor vehicle starting system including a starting switch and a starting pinion, means for jointly closing said switch and moving said pinion into starting position, a control pedal, a coupling linkage between said pedal and said means, a power element responsive to engine operation for controlling said linkage whereby said linkage is maintained inoperative during engine operation, means for holding said linkage in an inoperative position upon the stopping of the engine, and releasing means operable by one movement of said control pedal to restore said linkage to operative condition and by a second movement of said pedal to actuate said switch closing means.

2. The combination with a vehicle having an internal combustion engine, and a control for said engine, of a power element connected to said engine, a starting motor, a starting gear driven by said motor, a battery, a circuit for connecting said battery and motor, a normally open switch in said circuit, a mechanical linkage connected to said control for closing said switch, a movable coupling element in said linkage connected to said power element, means including said power element for moving said coupling element to render said linkage inoperative during the operation of said engine, means dependent upon operation of said control for restoring said linkage to operative condition upon stopping of the engine, and means for simultaneously engaging said starting gear and closing said switch, said control restoring means including an actuating member connected to said control for restoring said linkage to operative condition.

3. The combination with a vehicle having an internal combustion engine, and a control for said engine, of a power element connected to said engine, a starting motor, a starting gear driven by said motor, a battery, a circuit for con-

necting said battery and motor, a normally open switch in said circuit, a mechanical linkage connected to said control for closing said switch, a movable coupling element in said linkage connected to said power element, means including said power element for moving said coupling element to render said linkage inoperative during the operation of said engine, and means dependent upon operation of said control for restoring 5 said linkage to operative condition upon stopping of the engine, said movable coupling element comprising a laterally slid able latch bolt which in latched position renders said linkage inoperative, said control restoring means including an actuating member connected to said control for unlatching said bolt.

4. The combination with a vehicle having an internal combustion engine, and a control for said engine, of a power element connected to 20 said engine, a starting motor, a starting gear driven by said motor, a battery, a circuit for connecting said battery and motor, a normally open switch in said circuit, a mechanical linkage connected to said control for closing said switch, a movable coupling element in said linkage connected to said power element, means including said power element for moving said coupling element to render said linkage inoperative during the operation of said engine, and means dependent 25 upon operation of said control for restoring said linkage to operative condition upon stopping of the engine, said movable coupling element comprising a laterally slid able bolt having a latching abutment at one end and a spring 30 for maintaining said bolt in latched position, said control restoring means including an actuating member connected to said control for unlatching said bolt.

5. The combination with a vehicle having an internal combustion engine, and a control for 40 said engine, of a power element connected to said engine, a starting motor, a starting gear driven

by said motor, a battery, a circuit for connecting said battery and motor, a normally open switch in said circuit, a mechanical linkage connected to said control for closing said switch, a movable coupling element in said linkage connected to said power element, means including said power element for moving said coupling element to render said linkage inoperative during the operation of said engine, and means dependent 5 upon operation of said control for restoring said linkage to operative condition upon stopping of the engine, said movable coupling element comprising a laterally slid able latch bolt having a notch therein, said control restoring means including an actuating member connected to said control and cooperating with said notch to unlatch said bolt.

6. The combination with a vehicle having an internal combustion engine, and a control for said engine, of a power element connected to 20 said engine, a starting motor, a starting gear driven by said motor, a battery, a circuit for connecting said battery and motor, a normally open switch in said circuit, a mechanical linkage connected to said control for closing said switch, 25 a movable coupling element in said linkage connected to said power element, means including said power element for moving said coupling element to render said linkage inoperative during the operation of said engine, means dependent 30 upon operation of said control for restoring said linkage to operative condition upon stopping of the engine, means for simultaneously engaging said starting gear and closing said switch including a pivoted yoke, and a coupling 35 linkage between said control and said yoke, said control restoring means including an actuating member included in said linkage, said actuating member being pivoted on the same axis as said yoke.

ALBERT CALLSEN.
